UNITED STATES PATENT OFFICE

172,944

TRACTOR BUMPER

Bruno F. Arps, New Holstein, Wis., assignor to
Arps Corporation, New Holstein, Wis.

Application June 22, 1953, Serial No. 25,585

Term of patent 14 years

(Cl. D14—6)

To all whom it may concern:

Be it known that I, Bruno F. Arps, a citizen of the United States, residing at New Holstein, State of Wisconsin, have invented a new, useful, original, and ornamental Design for a Tractor Bumper, of which the following is a specification, reference being had to the accompanying drawing, forming a part hereof.

Figure 1 is a front view of a tractor bumper embodying my new design;

Figure 2 is a top plan view; and
Figure 3 is an end view thereof.

I claim:

The ornamental design for a tractor bumper, as shown.
